UNITED STATES PATENT OFFICE.

PETER MOQUIST, OF MINNEAPOLIS, MINNESOTA.

FURNACE.

1,296,306.

Specification of Letters Patent. Patented Mar. 4, 1919.

Application filed June 11, 1917. Serial No. 173,946.

To all whom it may concern:

Be it known that I, PETER MOQUIST, a citizen of the United States, residing at Minneapolis, in the county of Hennepin and State 5 of Minnesota, have invented certain new and useful Improvements in Furnaces; and I do hereby declare the following to be a full, clear, and exact description of the invention, such as will enable others skilled in 10 the art to which it appertains to make and use the same.

My invention relates to furnaces for heating systems, and has for its object to increase the efficiency thereof and, at the same 15 time, save fuel; and, to this end, it consists of the novel devices and combinations of devices hereinafter described and defined in the claims.

In the accompanying drawings, which 20 illustrate the invention, like characters indicate like parts throughout the several views.

Referring to the drawings,

Figure 1 is a front elevation of the improved furnace;

Fig. 2 is a plan view of the same with some parts broken away and with some of the exposed parts sectioned;

Fig. 3 is a view principally in longitudinal vertical section taken on the line 3—3 30 of Fig. 2;

Fig. 4 is a view partly in elevation and partly in longitudinal vertical section taken through the furnace of the boiler;

Fig. 5 is a transverse vertical section taken 35 on the irregular line 5—5 of Fig. 2; and

Fig. 6 is a transverse vertical section taken on the irregular line 6—6 of Fig. 2.

The numerals 7 and 8 indicate, respectively, a fire-box housing and a boiler housing laterally spaced, the one from the other, and connected at their rear ends by a secondary combustion chamber 9. As shown, the housings 7 and 8 and secondary combustion chamber 9 are all constructed of 40 masonry, except the front ends of said housings, which are closed by cast metal ends 10 and 11, respectively. In the front end of the fire-box housing 7, is a primary combustion chamber 12 having therein a grate 13

45 under which is an ash-pit 14. The front end 10 of the fire-box housing 7 is provided with double fuel doors 15 and double ash doors 16.

Extending rearward from the combustion 50 chamber 12 to the secondary combustion

chamber 9, are a plurality of horizontal main flues 17 that are spaced both vertically and horizontally and are supported on a bridge wall 18 of masonry and extend to the top of the housing 7. These flues 17, 60 as shown, are made in relatively short sections from baked clay that are rectangular in cross section with openings in the form of upright ovals.

In the front end of the boiler housing 8, 65 is a tertiary combustion chamber 19 with which the secondary combustion chamber 9 has communication through a multiplicity of secondary flues 20, preferably of the same form and construction as the main flues 70 17. These secondary flues 20 are supported on masonry 21, with the uppermost thereof in direct contact with a horizontal boiler 22 having upper and lower flues 23 and 24 and supported from the side walls of the 75 boiler housing 8. The lower boiler flues 24 connect the tertiary chamber 19 with a return chamber 25, at the rear end of the boiler 22, are supported upon the primary combustion chamber 9, as shown, and constructed of sheet metal. The upper boiler flues 23 connect the return chamber 25 to a smoke-stack chamber 26 from which leads a smoke-stack 27. The smoke-stack chamber 26 is located directly over the tertiary 80 combustion chamber 19 and is separated therefrom by a horizontal metal partition 28.

Access may be had to the tertiary combustion chamber 19 through double doors 90 29 formed in the front end 11 of the boiler housing 8, and access may be had to the smoke-stack chamber 26 through double doors 30, also formed in said front end 11. Extending through the top of the fire-box 95 housing 7 and opening into the fire-box 12, is a fuel feed hopper 31. The return water pipe to the boiler 22 from the system is indicated by the numeral 32.

Fresh air is supplied to the fire from 100 under the grate 13 through a conduit 33, in the top of the fire-box housing 7, down flues 34, return flues 35, air chamber 36, and a multiplicity of winding air ports 37. As shown, the fresh air conduit 33 is formed by providing the top of the fire-box housing 7 with two vertically spaced walls constructed of brick supported on the flanges of inverted T-rails 7'. Fresh air is admitted 105 to the conduit 33, through a door equipped 110

opening 38 in the upper wall of the top of the fire-box housing 7 and at the rear of the main flues 17.

- The down air flues 35 are formed in the 5 side walls of the fire-box housing 7 and afford communication between the forward end portion of the air conduit 33, with the corresponding end portions of the return air flues 35 also formed in said side walls.
- 10 The air chamber 36 extends transversely through the bridge wall 18 and affords a communicating passageway between the rear ends of the return flues 35. The air ports 37 are horizontally spaced, lead from the air chamber 36 and wind in vertical planes to points where they discharge through the bridge wall 18 under the grate 13. Dampers 39 are provided for controlling the air discharge from the ports 37.
- 15 Branch air ports 40 lead from the air ports 37 and have their delivery ends arranged to discharge into the secondary combustion chamber 9. The air discharged from these branch ports 40 is controlled by dampers 41.
- 20 The flames from the primary combustion chamber 12, passing through the flues 17 to the secondary combustion chamber 9, keep the same red-hot, so that all combustible matter therein continues to burn. The products of combustion in the secondary combustion chamber 9 will, of course, expand, but, upon entering the return flues 20, will not travel any faster than while traveling through the flues 17, for the reason that the 25 aggregate transverse area of the flues 20 over that of the flues 17 is materially increased by providing a greater number of flues 20. As the flues 20, like the flues 17, are red-hot, all unburned combustible matter, while passing therethrough and through the tertiary combustion chamber 19, will be consumed and, upon entering the lower boiler flues 24, will produce their greatest effect upon the 30 water in the boiler 22. From the lower boiler flues 24, the products of combustion, entering the return chamber 25, will pass to the smoke-stack chamber 26, through the upper boiler flues 23, again subjecting the water in the boiler 22 to their heat. From the 35 above description, it is evident that all combustible matter leaving the primary combustion chamber 12 is continuously subjected to the red-hot walls of the flues 17 and 20 and combustion chambers 9 and 19, so that the same is entirely consumed before reaching the boiler 22. By making the flues 17 and 20 oval shaped in cross section, the sides of adjacent flues are brought close together, so that they will heat quickly, and their 40 strength is increased to support the load thereon.

Fresh air, passing through the conduit 33 and flues 34, is heated from the primary combustion chamber 12 and flues 17, so that the same has a desired temperature, when

delivered under the fire on the grate 13 and into the secondary combustion chamber 9. By adjusting the dampers 39 and 41, the desired amount of fresh air may be delivered under the fire and into the secondary combustion chamber 9. 70

What I claim is:—

1. A furnace having primary, secondary and tertiary combustion chambers, main flues connecting the primary and secondary 75 combustion chambers, secondary flues connecting the secondary and tertiary combustion chambers, and a boiler having flues in communication with the tertiary combustion chamber. 80

2. A furnace having primary, secondary and tertiary combustion chambers, main flues connecting the primary and secondary combustion chambers, secondary flues connecting the secondary and tertiary combustion 85 chambers, and a boiler having flues in communication with the tertiary combustion chamber, said main and secondary flues being made from baked fire clay.

3. A furnace having primary, secondary 90 and tertiary combustion chambers, main flues connecting the primary and secondary combustion chambers, secondary flues connecting the secondary and tertiary combustion chambers, and a boiler having flues in 95 communication with the tertiary combustion chamber, said main and secondary flues being made from baked fire clay and each having a cross section that is in the form of an upright oval. 100

4. A furnace having primary, secondary and tertiary combustion chambers, main flues connecting the primary and secondary combustion chambers, secondary flues connecting the secondary and tertiary combustion 105 chambers, and a boiler having flues in communication with the tertiary combustion chamber, said secondary flues having a greater area in cross section than said main flues. 110

5. A furnace having primary and secondary combustion chambers, main flues connecting the primary and secondary combustion chambers, a tertiary combustion chamber, secondary flues connecting the secondary and tertiary combustion chambers, a boiler having upper and lower flues, a return chamber, and a smoke-stack chamber, said lower boiler flues connecting the tertiary combustion chamber and return chamber and said upper flues connecting the return chamber and the smoke-stack chamber. 115

6. A furnace having in its front end primary and tertiary combustion chambers, laterally spaced one from the other, a secondary combustion chamber at the rear end of the furnace, a return chamber over the secondary combustion chamber, a smoke-stack chamber over the tertiary combustion chamber, main flues connecting the primary and 120 125 130

- secondary combustion chambers, secondary flues connecting the secondary and tertiary combustion chambers, and a boiler located over the secondary flues and having upper 5 and lower flues, said lower flues connecting the tertiary combustion chamber and return chamber and said upper boiler flues connecting the return chamber and smoke-stack chamber.
- 10 7. A furnace having a fire-box housing and a boiler housing, laterally spaced one from the other, a secondary combustion chamber connecting the rear ends of said two housings, a primary combustion chamber in the front end of the fire-box housing, main flues connecting the primary and secondary combustion chambers, a tertiary combustion chamber in the front end of the boiler housing, secondary flues connecting
- secondary and tertiary combustion chambers, a boiler in the boiler housing supported over the secondary flues and having upper and lower flues, a smoke-stack chamber located in the boiler housing over the tertiary combustion chamber, and a return chamber 25 located over the secondary combustion chamber, the lower flues of said boiler connecting the tertiary combustion chamber and the return chamber and the upper flues of said boiler connecting the return chamber with 30 the smoke-stack chamber.

In testimony whereof I affix my signature in presence of two witnesses.

PETER MOQUIST.
